DIPPING TANK

Daniel C. Cooper, Chicago, Ill.

Application August 6, 1953, Serial No. 372,659

5 Claims. (Cl. 134—46)

This invention relates in general to dipping tanks, and more particularly to mechanism operable to immerse articles to be coated or cleaned into a tank containing a desired treating liquid and to automatically agitate the articles, while immersed, to effect a swashing movement thereof in the liquid.

A principal object of the invention is to insure complete contact or coating of articles to be treated with a desired liquid, and particularly articles having an irregular configuration or a rough surface or apertures or recesses therein, without requiring the application of the treating liquid by the use of external pressure.

Another important object is the provision of dipping tank mechanism which includes means for supporting articles to be treated and for immersing the same into the tank, together with control means for causing automatic repeated oscillation of the article-supporting means while the latter maintains the articles submerged.

A further object is to enable such control means to be selectively rendered inoperative so as to effect automatically repeated lowering and raising of the article-supporting means relative to the tank between extreme upper and lower positions.

Another object is to include manually operable control means in such dipping tank mechanism which may be selectively actuated to initiate or stop movement of the article-supporting means at any time.

A further important object of the invention is to avoid all possible fire hazards with such dipping tank mechanism, so as to enable the safe usage of flammable treating liquids, by employing pneumatically operated means for actuating the same, together with automatic fire-extinguishing means.

Another principal feature of this invention is the provision of a fire cover for such an open-top dipping tank normally constrained against movement from raised to lowered or closed position by a heat-fusible link, and means automatically actuated by the cover, during the initial portion of downward movement thereof, to actuate the control means so as to cause lowering of the article-supporting means or tray out of the path of movement of the cover if the tray is in any but its lowermost position.

More specifically, this latter feature comprises the provision of a fire cover for an open-top dipping tank having the aforementioned article-supporting tray and tray-actuating means automatically controlled by tray-actuated control members and a control member movable in response to movement of the cover, as the same starts to move toward tank-closing position, to actuate the normally automatically operated member which causes lowering of the tray. This system also is so arranged that, as the tray arrives in its lowermost position in response to such operation of the control member, it will terminate operation of the actuating mechanism.

Numerous other objects and advantages of the invention will be apparent as it is better understood from the

2

following description, which, when taken in connection with the accompanying drawings, discloses a preferred embodiment thereof.

In the drawings:

Figure 1 is a perspective view of a dipping tank embodying the features of the instant invention, showing the article-supporting rack or tray in an upper position and the fire cover latched in its normal raised position;

Figure 2 is a vertical side view in partial cross section;

Figure 3 is a top plan view, showing the fire cover in closed position;

Figure 4 is an enlarged detail view in partial cross section illustrating the fire cover;

Figure 5 is a detail view on an enlarged scale, showing the automatically operated fire cover release mechanism in cover-retaining position;

Figure 6 is a detail side view of the structure illustrated in Figure 5;

Figure 7 is a schematic showing of the electrical control circuits associated with the structures of the foregoing drawings; and

Figure 8 is a detail view, in partial cross section, of structural elements of the invention arranged for movement substantially within the dipping tank of Figure 1.

Referring more particularly to the drawings, reference numeral 11 generally indicates a dipping tank of any suitable construction comprising a front wall 12 (Fig. 2), rear wall 13, bottom 14, right side or end wall 15 (Fig. 3), and left wall 16. These several wall members may be mounted and secured together in any desired manner and reinforced by means of suitable corner angles 17 and upper marginal rails 18. 11a indicates a valved drain for the tank 11. The tank 11 is open at its top and is provided with a fire cover, indicated generally by reference numerals 19, which is shown in the present embodiment (Fig. 1) as comprising two doors 19 hingedly mounted and normally maintained in substantially upright or raised position each adjacent one of the walls 15 and 16 of the tank. 19a indicates an auxiliary edge

fire door hingedly mounted on one edge of the tank 11 running between the side edges to which the doors 19 are hinged and adapted to surround certain mechanism extending upwardly above and from inside the tank 11. The member 19a is formed to ride upon the movable elements of this mechanism as it rises and lowers from and into the tank 11. Such mounting of the fire covers 19 includes a pair of arms 21 secured at their inner ends in any suitable manner to each door and pivotally mounted at their outer ends at 22 on suitable brackets 23 extending from the tank and mounted thereon at their inner ends in any desired manner. Latch mechanism is provided for normally maintaining the cover or covers 19 in the raised position of Figure 1 which comprises hooks 24 pivotally mounted at their outer ends on upstanding arms 23a and engaging a latch hook 25 which in turn is pivotally mounted at 26 on each of the doors 19. This latch hook 25 extends through the cover and normally is constrained against pivotal movement in a clockwise direction (viewing Fig. 6) by a heat-fusible link 27.

As will be readily understood, if the treating liquid contained in the tank 11 catches fire, the link 27 will be fused by the resultant heat to release the hook latch 25 for such pivotal movement in response to the weight of the cover 19, the hooks 24 and 25 thus being disengaged automatically to permit the cover to swing about its pivot 22, in response to gravity, downwardly into tank-closing position. A spring 24a is secured to the hook 24 and to the arm 23a below the hook 24 to bias it downwardly toward the tank and against the nose 25a of the latch hook 25. Thus when the link 27 is fused the spring 24a is effective to snap the hooks 24

and 25 out of engagement. When the hooks are disengaged the spring 24a biases the hook 24 into engagement with the abutment 24b. This abutment positions the hook 24 in the line of movement of the latch hook 25 so that it will cam under the hook during latching of the doors 19 when they are raised.

The tank 11 also includes a pair of angle-shaped guide members 28 secured by welding, or the like, to the inner surface of the rear wall 13 (Fig. 1) which are spaced laterally from each other and extend vertically from the bottom of the tank to a substantial distance above the marginal rails 18. These angle members 28 and the rear wall 13 comprise means for guiding an article-supporting rack or tray, indicated generally by reference numeral 29, in vertical movements relative to the tank 11. This rack 29 comprises a horizontal frame portion 31 secured to a lower portion of a set of vertically upwardly extending arms 32, 32a, 32b and extending forwardly therefrom, the frame portion and vertical arms being additionally rigidly interconnected by angularly disposed side or end members 33 and cross-bar 33a therebetween. The rack 29 may support a lattice-work or perforate basket 34, mounted on the horizontal frame 31, which preferably is constructed of a plurality of transversely and longitudinally extending bars mounted in upright position or on edge in spaced relationship to each other and secured together by welding, or the like, in a grill arrangement. The horizontal frame 31 and vertical arms 32, 32a, 32b preferably are made up of angle irons, and the latter includes the pair of vertically disposed angle bars 32, 32a spaced laterally from each other so as to be disposed each adjacent one of the tank guide members 28 when the rack 29 is mounted in the tank. Each of these vertical angle members 32, 32a has a pair of rollers pivotally mounted thereon in vertically spaced relationship to each other. The upper of each such pair of rollers 36 is mounted slightly forward of the related lower roller 37, so that the two upper rollers 36 engage the respective guide members 28, while the two lower rollers 37 engage the rear wall 13, when the vertical arms 32, 32a, 32b are in parallel relationship to the rear wall 13 of the tank. Thus it will be seen that, in addition to guiding vertical movement of the rack or tray 29 relative to the tank 11, these rollers 36, 37, the angle members 28 and the rear wall 13 also support the horizontal frame 31 and basket 34 against forward tilting movement. Indicated at 28a is a second pair of angle members secured to the inner face of the wall 13 and having runners extending perpendicularly therefrom into the tank. The tray 29 has rollers 36a, 37a secured thereto for rotation between and against the opposing surfaces of the angle members 28a and thus in a plane perpendicular to the plane of rotation of the rollers 36, 37. Thus the tray 29 is prevented from sideways movement also.

Means are provided for actuating the tray 29 to move the same between its lowermost full line position of Figure 2 and an upper position illustrated generally in Figure 1, wherein the upper edges of the basket 34 are spaced above the marginal rails 18 of the tank. This tray-actuating means is indicated generally by reference numeral 38, and includes a double-acting pneumatic piston 39 encased within a vertically disposed cylinder 41 mounted on the tank-supporting surface to the rear of the tank and preferably secured to the rear wall 13 by means of suitable brackets 42. The piston 39 has an elongated piston rod 43 secured thereto, the upper end of which is reversely bent relative to the main portion thereof, extends downwardly parallel thereto and is secured at its lower terminal portion in any suitable manner to the vertical arm 32b of the article-supporting rack or tray 29. This movement of the piston 39 in its cylinder 41 will be accompanied by similar vertical movements of the rack or tray 29 relative to the tank 11 and,

by virtue of the rigidity of this structure and the substantial length of the piston 39, the same will assist the rollers 36, 37 and guide members 28 and rear wall 13 in preventing unwanted movements of the rack in any horizontal plane relative to the tank.

The cylinder 41 may be pivotally mounted, adjacent its lower end, to the tank 11 and bracket 42, as at 42a, to provide for ease in maintenance and repair without removal of the cylinder from the tank.

A suitable source of supply of air under pressure is provided for actuating the double-acting piston 39 which is illustrated herein as a main air line 44 (Fig. 1) any suitable compressor means being employed to supply the desired air pressure thereto but not being illustrated herein. The main air line 44 may have an auxiliary air line connected thereto for supplying compressed air to a standard manually operated cleaning nozzle. Connected in series in this main supply line 44 is a filter 46, a pressure gauge 47, an oiler 48, all of standard construction.

Following the oiler 48 is a four-way master control valve 50, which is the standard electrically controlled four-way air valve. The main air control solenoid valve 50 may direct the flow of air from the line 44 to an air conduit 51 interconnected between the master control valve 50 and the lower end of the main air cylinder 41, or to an upper air conduit 52 which interconnects the master control valve 50 and the upper end of the main cylinder 41. It will be understood that the air on the approaching side of the piston 39 is exhausted through the inlet lines 51, 52 and back through the main air valve 50.

A means to selectively effect control of air under pressure from the main supply line to the lower and upper ends of the cylinder 41 is illustrated in Figures 1 and 7. While it will be understood that a system of solenoids, air valves, etc., may be employed for this purpose, I find the system shown to be preferable. 60 generally indicates a master switch of the "start-stop" type and having the manually operable push-button "start" or "down" switch 61 and "stop" or "up" switch 62. Conduits leading from the switch 60 to the main air control valve 50 and therefrom to limit switches 70 and 71 are indicated, respectively at 63, 64, 65. The limit switches 70—71 are secured to the rear wall 13 in vertical alignment adjacent the cylinder 41.

The "up" limit switch 70 has pivoted thereon the switch arm 80. Rotatably mounted on the outer end of the switch arm 80 is the cam-actuated roller 81. The "down" limit switch 71 has pivoted thereon a switch arm 82, having at its outer end the cam actuated roller 83 in vertical alignment with the roller 81. Secured to the piston rod 43 adjacent the top bent portion thereof, as by the bracket 84, is the elongated rod 85 arranged in spaced parallel relationship with the vertical portion of the piston rod 43. Secured to the lower end of the rod 85 is the cam-block 86. When the tray 29 is mounted on or in the tank 11 the cam-block 86 is in vertical alignment with the rollers 81, 83. The cam 86 is effective to close the down limit switch 71 when the tray approaches its lowermost position and to close the up limit switch 70 when the tray 29 approaches its uppermost position. It will be realized that this closing of the limit switches 70—71, through appropriate electrical conduits, switches and timing devices, such as those illustrated in Figure 7, is effective to reverse, through the main air valve 50, the direction of travel of the piston 39 and tray 29. When, on the other hand, the tray 29 is at either its full upper or lower position, the cam 86 has passed the rollers 81, 83 and the limit switches are rendered ineffective. It will be understood that the placement of the limit switches 70 and the length of full stroke of the piston 39 are such that the limit switches 70—71 cause a reciprocation of the tray 29 within and adjacent a lower portion of the tank 11, that is to say, once the tray 29 reaches its uppermost position shown in Figure 1 it will remain there, having passed the limit switch 70, until the down switch

60 is actuated. In order to cause the tray 29 to reach its uppermost position it is necessary only that the operator push and hold in the "up" switch 62 until the cam 86 has passed upwardly beyond the roller 81, the held-in switch 62 being effective to render inoperative the limit switch 70.

Flow-restricting valves are indicated at 90 and 91 in the conduits 52 and 51. The valves 90 and 91 may be adjusted to determine the proper rate of flow of the air under pressure into the cylinder 41 to effect the desired rate of movement of the piston 39 and the rack or tray 29. These valves 90 and 91 function to restrict the flow of air only in the direction toward the cylinder 41. Consequently, when the air supply is flowing into the upper end of the cylinder 41, that air in the lower portion of the cylinder is exhausted therefrom through the lower conduit 51 and the master control valve 50. Conversely, when the air is being supplied through the lower conduit 51 to the lower end of the cylinder 41, the air previously supplied to the upper portion of the cylinder is exhausted therefrom through the upper conduit 52 and the master control valve 50. It will be understood that the valve 50 is so designed as to effect alternate connection between the conduits 41 and 51 and connection of the conduit 52 to the atmosphere, and interconnection of the conduits 44 and 52 and connection of the conduit 51 to the atmosphere, for example through an exhaust 93 shown in Figure 1. The weight of the rack or tray 29, the piston rod 43 and the piston 39, together with that of the articles being treated and supported by the tray, will assist the downward movement of the rack and retard its upward movement. Consequently, the flow-governing valve 91 may be adjusted to compensate for these differences in component forces applied to the rack during raising and lowering, or a separate valve may be added in the conduit 51, restricting the exhaust flow of air from the lower portion of the cylinder 41 during downward movement of the rack. Thus the same rate of movement of the rack 29 downwardly will result as obtains during raising of the rack with the same air pressure in the supply line.

As previously noted, if the treating fluid in the tank 11 or the residual thereof on articles being treated or the rack 29 should catch on fire, the link 27 will be fused to release the latch 25 from the hook lever 24 to permit the covers 19 to fall into tank-closing position. However, if the rack or tray 29 is not in its lowermost position, the same will prevent closing of the covers 19. Means are provided, therefore, for automatically operating the above-described control mechanisms, in the event of release of the covers 19 for closing, to effect movement of the rack or tray 29 to its lowermost position by the actuating mechanism 38. This rack-lowering control mechanism is automatically actuated during that initial portion of downward swinging movement of the covers 19 which may be made by the latter before any interference is had with the rack 29 when the latter is in its uppermost position.

Referring to Figure 1, a switch 100 is mounted, as by the pipe-conduit 101, on the upper wall of the main switch 60. Electrical wiring extends from the switch 100 through the pipe 101 to connect the switch 100 into the electrical system. The switch 100 has a spring loaded switch arm or cam lever 103 extending upwardly therefrom and pivotally mounted thereon. A cam roller 104 is rotatably mounted at the upper end of the arm 103. Since the arm 103 extends above the upper level 18 of the tank adjacent one side thereof and since it is spring-biased inwardly toward the tank, the roller 104 is held constantly in contact with the outer surface of a cover 19 when the covers are in upright position. As soon, however, as the cover 19 begins to fall downwardly as a result of a fire, for example, the arm 103 snaps inwardly toward the tank 11, thus closing the switch 100 and, through appropriate circuits such as those indicated

schematically in Figure 7, actuating the "down" switch 61 to cause the tray 29 to move downwardly. Since this action would be ineffective if the tray 29 were caused to rise immediately, as would be normal due to the action of the limit switch 71, the actuation of the switch 100, in effect, holds "down" switch 61 in and renders inoperative the limit switch 71 and thus permits the cam 86 to pass beyond the roller 83 and the tray to reach its lowermost position, where it remains due to the setting of the main valve 50 in the "down" setting. When it is desired to again raise the tray 29 it is necessary to raise the covers 19, thus deactivating the switch 100, and to press the "up" switch 62, which, since the switch 100 is inoperative, renders the limit switch 71 again operative and the reciprocating action will continue.

It will be realized that whereas I have described and illustrated a practical and operative device, nevertheless, many changes may be made in the size, shape, number and disposition of parts without departing from the spirit of my invention. I, therefore, wish my description and drawings to be taken as in a broad sense illustrative or diagrammatic, rather than as limiting me to my precise showing.

I claim:

- 25 1. A dipping tank, comprising a liquid-containing tank having an upwardly open top, a hinged cover for said top of said tank, a tray for supporting articles to be treated, tray actuating means mounted exteriorly of the tank and connected to said tray for moving the tray vertically into and out of the tank, control means for controlling operation of said actuating means, selectively operable control members for determining the direction of movement to be imparted to said tray by said actuating means, a control member operating device mounted on said actuating means for operating said control members to automatically effect repeated vertical reciprocation of said tray by said actuating means for a relatively short distance adjacent the bottom of the tank, said control means including mechanism operable in response to movement of the cover toward closed position to automatically render inoperative said control member operating device and to terminate the operation of said actuating means when said tray is entirely below the top of said tank.
- 45 2. A dipping tank, comprising a liquid-containing tank having an upwardly open top, a hinged cover for said top of said tank, a tray for supporting articles to be treated, tray actuating means mounted exteriorly of the tank and connected to said tray for moving the tray vertically into and out of the tank, control means for controlling operation of said actuating means, said control means including a manually operable member for initiating and terminating operation of said actuating means, selectively operable control members for determining the direction of movement to be imparted to said tray by said actuating means, a control member operating device mounted on said actuating means for operating said control members to automatically effect repeated vertical reciprocation of said tray by said actuating means for a relatively short distance adjacent the bottom of the tank, said control means including mechanism operable in response to movement of the cover toward closed position to automatically render inoperative said control member operating device and to move said manually operable member to terminate operation of said actuating means when said tray is entirely below the top of said tank.
- 55 3. In a liquid-containing tank having a tray for supporting articles to be treated, dipping mechanism, comprising actuating mechanism for moving said tray between an upper position for receiving the articles and a lower position within the tank to immerse the articles in the liquid therein, and control mechanism rendered automatically operable by said tray during its upward movement from said lower position to cause said actuating

mechanism to return the tray toward said lower position before the articles emerge from the liquid, a hinged cover on said tank and automatic shutoff means operatively connected with said cover and with said control mechanism and effective, in response to movement of said cover toward closed position, to terminate operation of said actuating mechanism and said control mechanism with said tray in its lower position.

4. The structure of claim 3 wherein said automatic shutoff means comprises a switch, said switch having a control arm held in nonoperating position by said cover when said cover is in its open position.

5. The structure of claim 3 wherein said automatic shutoff means comprises a spring-loaded switch having a control arm held in non-switch-operating position by said cover when said cover is in its open position, said switch being electrically connected with said actuating mechanism and said control mechanism and effective, in response to movement of said cover toward its closed

5

position, to direct said tray toward its lowermost position and to terminate operation of said actuating mechanism and said control mechanism.
